UNITED STATES PATENT OFFICE.

DONALD NOBLE, OF BRIDGEPORT, CONNECTICUT, ASSIGNOR TO THE SINGER MANUFACTURING COMPANY, A CORPORATION OF NEW JERSEY.

PERFORATING-MACHINE.

1,382,378.

Specification of Letters Patent. Patented June 21, 1921.

Application filed July 14, 1919. Serial No. 310,690.

To all whom it may concern:

Be it known that I, DONALD NOBLE, a subject of the King of Great Britain, residing at Bridgeport, in the county of Fairfield and State of Connecticut, have invented certain new and useful Improvements in Perforating-Machines, of which the following is a specification, reference being had therein to the accompanying drawings.

10 This invention relates to a machine for operating upon leather or other sheet material and is more specifically intended as an improvement upon the perforating machine disclosed in the application of Donald Noble, 15 Ser. No. 232,744, filed May 6, 1918, although certain features of the present invention are equally applicable to perforating machines of other types.

Machines of the above character are normally intended for forming series of small perforations in sheet material by a succession of rapidly repeated blows, and the feeding of the work into position for forming the successive perforations is accomplished by a 25 lateral movement of the punch carrier while the punch is in engagement with the work.

These machines are at times employed for forming a series of scallops along the edge of the material, employing for this purpose a 30 punch having a substantially semi-circular cutting edge. In making use of a punch of this character difficulty is experienced in securing a proper feed of the work, as the punch frequently slips along the edge of the 35 material without moving the latter to the proper distance thus producing defective work.

The present invention provides material feeding means associated with the punch 40 carrier and having a lateral reciprocating movement sufficient to properly feed the work regardless of the type of punch employed.

This invention further contemplates feed 45 mechanism for the material having elements contacting with opposite sides of the material and which serve to positively grip the material for moving it in the direction of feed.

50 In machines of the character above noted it is usual to fix the punch in a holder which is removably mounted in the punch carrier. As the punches employed must be varied in

accordance with the pattern to be formed in the material, it is necessary for the operator 55 to remove the punch holder at frequent intervals from the carrier to permit the substitution of another having differently shaped or arranged punches. In replacing the holder it is very important that it shall not 60 drop from its proper position in the carrier while the operator is tightening the retaining clamp or upon any inadvertent loosening of the clamp during operation, as such an occurrence may cause the punch-holder to 65 protrude so far from the carrier as to cause serious damage to the machine upon reciprocation of the carrier.

This invention provides for preventing such an accident by furnishing the punch 70 holder and carrier with interengaging parts which are automatically brought into holding relation upon insertion of the holder in the carrier and which retain the holder in proper position during the tightening of the 75 holding clamp and prevent dropping of the holder if the clamp becomes loose during operation of the machine.

The present invention further provides a 80 novel and simple means for securing the individual punches in the holder whereby they are firmly positioned during operation, but which permits the ready removal of punches therefrom when necessary for repair.

Other objects and advantages of the present 85 invention, together with improved details of construction and advantageous combinations of parts will be hereinafter more fully described in the specification and particularly set forth in the claims, reference 90 being had to the annexed drawing as disclosing a preferred embodiment thereof and in which,—

Figure 1 is a partial transverse section to enlarged scale through the punch carrier 95 showing the punch holder and chip agitator in front elevation;

Fig. 2 is a transverse section to enlarged scale through the punch carrier, punch holder and chip agitator looking from the 100 front;

Fig. 3 is a bottom plan view of the parts shown in Fig. 1;

Fig. 4 is a cross section on the line $a-b$ Fig. 1, looking in the direction of the 105 arrows;

Fig. 5 is a diagrammatic detail showing the type of work performed by the punch herein disclosed;

Fig. 6 is a view similar to Fig. 2 but relating to a modified form of the device; and

Fig. 7 is a bottom plan view of holder 74 illustrating the employment of a modified form of feed member.

The present invention is designed more particularly for embodiment in the type of machine disclosed in the application of Donald Noble, Serial No. 232,744, filed May 6, 1918, to which application reference may be had for a full disclosure of details of construction not herein shown.

65 is a bearing bracket mounted upon the machine frame, said bracket being adapted to have imparted thereto a reciprocating movement in the direction of work feed. Such movement may be imparted by the mechanism disclosed in the above referred to application or in any other suitable manner. The bearing member 65 has mounted therein for vertical sliding movement a tubular punch carrier 67 the latter comprising an upper portion of cylindrical form of relatively small diameter and a lower tubular portion 68 of greater diameter, the interior of which forms a receiver 95 for punchings or chips removed from the material when a tubular punch is employed. The enlarged lower portion of the punch carrier is provided at 69 with a pair of opposed bearing bosses of which one only is shown, said bosses being pivotally supported in the lower ends of operating links 59, 60, such links being adapted to receive a vertical reciprocating motion by means of cams or in other suitable manner, the particular mode of operating these parts not being within the scope of the present invention. Screws 70, 71 having enlarged heads are engaged with threaded openings in the bosses 69 and serve to hold the links 59, 60 in proper relation thereto.

The lower extremity of the tubular punch carrier is open and is arranged for the reception of a sleeve 73 integral with the disk 74, which, together with the disk 75, comprises the punch holder. Disk 75 has one or more suitable taper openings (a single, central opening being illustrated herein) for the reception of the shank portions of punches of the desired character. The disk 74 is provided with an opening 76^a of a diameter substantially equal to the internal diameter of the punch shank and co-axial with the opening in disk 75. The punches are inserted from the upper side of disk 75 which is then secured in position by means of screws 74^a, the upper or rear end of the punch shank thus resting against plate 74 which serves as an abutment therefor. By separating disk 75 from disk 74, the punch may readily be removed for repair or re-

placement by subjecting it to a slight blow upon its forward or cutting extremity. While the device herein disclosed is entirely suitable for holding and using tubular punches, it is particularly intended for use with open punches, such for example as that shown at 76, having tubular shank portions and substantially semi-circular cutting edges 76^x.

The punch carrier is longitudinally slit at its lower extremity near the rear portion thereof to form a slot 68^a, and is provided with a pair of outstanding gears 77 located on opposite sides of said slot through which is passed a bolt or screw 78, by means of which the opposite edges of the slot may be drawn together, thereby decreasing the interior diameter of the tubular punch carrier, which is of sufficiently resilient material to permit such action, whereby the sleeve 73 may be securely clamped within the extremity of the punch carrier. 79 indicates an opening or passage leading from the interior of the portion 68 of the punch carrier to permit the discharge of chips cut by tubular punches when such are employed, such chips being permitted to pass up into the interior of the part 68 by reason of the opening 76^a formed in the disk 74.

Located within the chip-receiving cavity 95 of the part 68 is a hollow cylindrical piston-like device 82 constituting a chip agitator, such device being provided with a closed upper end or head 83 serving to adjustably limit the capacity of said cavity for receiving chips discharged upwardly and into the chip agitator. The chip agitator is formed with a portion 84 of reduced diameter, the main body of said chip agitator being of substantially the internal diameter of the lower portion 68 of the carrier, while the reduced portion 84 thereof fits within and slidably engages the sleeve 73 of the punch holder. The chip agitator is provided in its side wall with a chip discharge opening 85, this opening being adapted to register with the opening 79 in the carrier 68. In order that the openings 85 and 79 may properly register the opposite sides of the chip agitator are provided with slots 86 arranged for engagement by the extremities of the screws 70, 71 which project inwardly beyond the walls of the carrier for this purpose, whereby any turning movement of the chip agitator is prevented. As it is desirable that the punch holder be readily positioned with the punches carried thereby in proper alignment with the direction of feed movement, the sleeve 73 of the punch holder has been provided with a centrally disposed V-shaped notch 87 and the chip agitator 82 is provided with a corresponding V-shaped lug 88. By this construction it is only necessary to introduce the punch holder into the lower extremity of the punch carrier and to

turn the same until said lug 88 registers with the notch 87, in order to properly position the punch holder with respect to the punch carrier, whereupon the clamping 5 screw 78 may be tightened to properly clamp the punch holder in operative position.

Extending upwardly from the closed head 83 of the chip agitator 82 is a rod 89 which 10 may be fixed to said chip agitator in any desired manner. This rod passes up through the tubular portion of the punch carrier 67, the upper end of which is closed at 89^a and is provided with an opening 89^b serving to 15 center the upper end of the rod 89. Between the head 89^a and the head 83 of the chip agitator is a spring 91 surrounding the rod 89 and positioned thereby, said spring being so tensioned as to cause the chip agitator 82 to move downwardly within the chamber 95 and normally to seat its lug 88 within the notch 87.

129 is an anvil member arranged in opposition to the punch for receiving the blow 25 thereof and for supporting the material during the punching operation, such anvil having a surface 134 over which is arranged to be drawn a strip of paper P, such paper serving to cushion the blow of the punch 30 and prevent damage to the edge thereof. Such cushion strip in the machine of the above noted application is fed rearwardly intermittently by suitable mechanism in time with the feeding movement of the 35 punch carrier and in accordance with the present invention it is contemplated that such movement of the paper strip shall be simultaneous with and of the same extent as the feed movement of the carrier, it being 40 understood that any desired type of mechanism suitable for the purpose may be employed. Y indicates a strip of material resting upon the paper strip P in position to be operated upon by the punches and in 45 Fig. 5 such strip is shown as having been scalloped along its edge by the employment of a punch having a substantially semi-circular cutting edge such as herein shown.

Guided within an opening 301 in the 50 punch holder is a rod 302, such rod extending upwardly within the chip agitator and being provided with a collar 303 which serves to retain it in proper position. The lower extremity of said rod at 304 is adapted 55 to rest upon the upper surface of the material Y while the upper extremity of said rod is arranged to engage a lug 305 projecting from the interior surface of the chip agitator. The sleeve 73 of the punch holder 60 is provided with a circumferential groove 307 and the interior of the tubular portion 78 of the carrier adjacent its open extremity is provided with a pair of outstanding arcuate ribs 308, 309, such ribs extending in 65 opposite directions from the slot 68^a and

gradually diminishing in radial height from said slot toward their opposite extremities.

The operation of the above disclosed mechanism is as follows, it being understood that the punch carrier 68 is vertically reciprocated by means of the links 59, 60 from a suitable source of power and that when the punch is down in engagement with the work the bracket 65 is moved rearwardly in the direction of feed to an amount corresponding to the spacing of the perforations to be formed. The mechanism herein disclosed is equally capable of use with hollow tubular punches for forming perforations, or semi-circular punches forming scallops 80 as above described.

As the punch 76 descends on the work resting on the upper surface of the paper strip P the lower extremity 304 of the rod 302 which extends to a point somewhat 75 below the cutting edge of the punch contacts with the surface of the material just prior to the contact of the edge of the punch therewith. As the punch carrier now moves down in performing the punching operation, the rod 302 bears firmly against the upper surface of the material, and during the latter part of the down stroke of the punch serves by engagement with the lug 305 to slightly raise the chip agitator 82 90 in the cavity 95 in opposition to the action of spring 91, said spring thus serving to resiliently press the rod 302 against the material. While the punch is in the material the bracket 65 is moved rearwardly and 100 simultaneously therewith the strip of paper P is given a rearward movement of like extent. The material Y being operated upon is thus gripped or pinched between the upper surface of the paper and the 105 lower extremity 304 of the rod 302 and is thereby positively carried rearwardly to the desired amount regardless of the type of punch employed being capable of operation to feed the material even in the entire absence of a punch. At the end of the rearward feeding movement of the bracket 65 the punch carrier is again raised lifting the rod 302 from the work, whereupon the 110 spring 91 again forces the chip agitator 82 115 downward in the cavity 95, the upward and downward movements of the chip agitator serving to keep the chips free in the receiving cavity and to insure their proper discharge therefrom. It will thus be seen that 120 the rod 302 has a two-fold function in serving as the feeding member for the material and also as an actuator for the chip agitator.

In changing punch holders as is often necessary in the employment of machines 125 of this character, due to breakage of punches, or to changes in the type of punch to be employed, the operator sometimes fails to hold the punch holder properly in position while tightening the clamping screw 78, 130

whereby the punch holder is caused to project below its proper position which frequently results in the smashing of the parts upon starting the machine. Furthermore, 5 during the operation of the machine it has sometimes occurred that the screw 78 would become loosened permitting the punch holder to drop, thus also producing disastrous results. In the present form of the 10 invention the operator in positioning the punch holder loosens the screw 78 which permits the opposite portions of the tubular carrier 68 to expand, thus increasing the width of the slot 68^a. The sleeve portion 73 15 of the punch holder is thereupon inserted in the end of the tubular carrier and pushed up until the ribs 308, 309 snap into the groove 307 which serves to temporarily hold the punch holder in position while the operator is tightening the clamping screw, the 20 resiliency of the tubular carrier, however, permitting the operator to withdraw the holder from the carrier by the application of sufficient force, upon release of the screw. 25 This arrangement of parts has been found in practice to insure the proper retention of the punch holder in its carrier at all times, thereby avoiding breakages of parts and requiring less care on the part of the operator. 30

A modified form of the work feeding device hereinbefore described is shown in Fig. 6, it being found in some cases desirable to have the feed element operate very close to 35 the cutting edge of the punch, such position of the feed element facilitating the operation of the machine in cutting scallops in curved lines wherein it is necessary to turn the work as the operation progresses. This 40 arrangement further avoids the formation of impressions in the surface of the material by the feed element at a distance from the edge which in some cases is objectionable.

In the form shown in Fig. 6, the punch 45 carrier 67, punch holder, chip agitator 82, punch 76 with open cutting edge 76^x are all similar to those hereinbefore described, the punch holder being also provided with the usual chip discharge opening 76^a. As in the 50 use of an open punch of the type herein disclosed, no chip passes up into the chamber 95, the opening 76^a is therefore unnecessary for permitting the passage of such chip and in the modified form this opening is made 55 use of for guiding a work feed member comprising a pin 200, the lower end of which lies substantially within the hollow portion of the punch, and substantially concentric with the cutting edge thereof. The upper 60 end 201 of the part 200 is of enlarged diameter to retain the part in proper position in the guide opening 76^a, and the upper extremity of the member 201 engages the lower part of a spider-like head 202 at the

lower end of rod 203 located within the chip 65 agitator 82, the head 202 serving as a guide to properly position the member 203, the upper end of which rests against the lower surface of the head 83 of the chip agitator. 70

This arrangement of parts operates in 75 substantially the same manner as does the device shown in Fig. 1, the operation of which has already been described, the only essential difference being that in the present case the feed member rests upon the work 80 substantially within the scallop cut by the punch, whereas in the earlier described device the feed member contacts with the work at a substantial distance from the edge thereof, it being understood that in this 85 form of device the pressure of the feed member upon the work is transmitted by the part 203 to the chip agitator as usual and serves to raise the latter slightly against the pressure of spring 91 which thus serves to 90 resiliently press the feed member against the work.

By reason of the spider-like head 202 95 chips are free to pass throughout the length of the chip agitator as usual and the feed 100 device herein described may be used if desired even when tubular punches are employed provided the latter are suitably grouped about the centrally located feed member.

In Fig. 7 is shown in bottom plan a modified form of the feed member in which the rod 302^x is provided at its lower extremity with a crescent shaped foot 500 which may be arranged to partially encircle the punch or punches employed and which provides a work contacting surface of sufficient extent to avoid the formation of undesirable impressions or marks on the surface of the material. 105

Having thus described the invention, together with the preferred embodiment of the same and the mode of operation thereof, what I claim and desire to secure by Letters Patent of the United States is:—

1. A machine of the class described having, in combination, a reciprocable punch carrier, a punch carried thereby, and a work feeding element mounted upon said punch carrier and movable therewith. 115

2. A machine of the class described having, in combination, a punch carrier reciprocable in a direction parallel to the feed of the work, a punch carried thereby, and an element for feeding the work, said element being reciprocable in time with the punch carrier. 120

3. In combination in a perforating machine, a punch carrier reciprocable in planes respectively substantially perpendicular and parallel to the surface of the material to be operated upon, a cutting tool mounted upon said carrier and a work feeding element as 125

sociated with said carrier and reciprocable therewith in a direction parallel to the surface of the material.

4. A perforating machine having, in combination, a punch carrier reciprocable in directions substantially at right angles to one another, a punch carried thereby and a work feeding element associated with said carrier and partaking of its movement in both directions.

5. A machine for operating upon sheet material having, in combination, a reciprocable tool carrier, a tool mounted thereon, and a yieldable work contacting feed element associated with said carrier and reciprocable therewith.

6. A machine for operating upon sheet material having, in combination, a tool carrier movable parallel to the direction of feed of the material, a tool mounted thereon and a work contacting feed element mounted upon said carrier and arranged to resiliently yield in a direction perpendicular to the surface of the work.

25 7. In a machine for perforating sheet material, in combination, a punch carrier arranged to have imparted thereto a movement in the direction of work feed, a punch mounted upon the carrier and means movable in time with the punch and carrier and engaging opposite sides of the material to impart thereto a feeding movement.

35 8. A machine for perforating sheet material having, in combination, a punch carrier arranged to have imparted thereto a work feeding movement, a punch carried thereby, a work contacting feed member mounted upon said carrier and arranged to engage one side of the material and a second feed element arranged to engage the opposite side of the material and to have imparted thereto a feed movement in time with that of the carrier.

45 9. In a machine for perforating sheet material, in combination, a punch carrier having a punch mounted thereon, and elements for engaging and gripping the material upon opposite sides thereof to impart thereto a feeding movement, one of said elements being resiliently mounted upon said carrier.

50 10. In a perforating machine, in combination, a reciprocable punch, a carrier therefor arranged to have imparted thereto a work feeding movement, a paper strip for supporting the material in opposition to the blow of the punch and movable intermittently in the direction of feed in time with the movement of the carrier, a work feeding element mounted upon the carrier and resilient means for pressing said element into engagement with the work.

60 11. In combination in a perforating machine, a punch carrier reciprocable substantially parallel to the direction of work feed,

a punch carried thereby, and a work contacting feed element supported by said carrier and comprising a rod slidably in said carrier and a spring for forcing said rod outwardly of said carrier and toward the work.

65 12. In combination in a machine of the class described, a tool carrier reciprocable substantially parallel to the direction of work feed, and a work contacting feed element comprising a rod slidably supported by said carrier, a spring for projecting said rod outwardly of said carrier and into contact with the work, and means for limiting such outward movement of the rod.

70 13. In combination in a machine of the class described a punch, a carrier therefor having a receptacle therein for chips cut by the punch, a device for agitating chips within said receptacle and means for actuating said device comprising an element arranged to contact with the work.

75 14. In a perforating machine, in combination, a punch carrier reciprocable toward and from the work, and provided with a cavity, a reciprocatory chip agitator within said cavity, resilient means for projecting said agitator toward the extremity of said carrier and means arranged to contact with the work upon operative movement of the carrier and to move said agitator in opposition to said resilient means.

80 15. In combination in a perforating machine a reciprocable hollow punch carrier, a chip agitator in the form of a sleeve slidably within said hollow carrier, means for retaining said sleeve within said carrier, a spring for resiliently moving said sleeve toward the extremity of the carrier, and a rod slidable relatively to said carrier and having one end thereof operatively associated with said sleeve and having its opposite extremity arranged for contact with the work.

85 16. In combination in a perforating machine, a reciprocable punch carrier comprising a tubular portion having an open extremity, a chip agitator in the form of a sleeve slidably within said tubular portion, a punch holder mounted upon said carrier and forming a closure for the open end thereof, and a rod or pin slidably guided in an opening in said holder and having one end operatively associated with said sleeve.

90 17. A machine of the class described having, in combination, a reciprocable punch carrier, a punch carried thereby and provided with an arcuate cutting edge, and a work feeding element mounted upon said punch carrier and substantially concentric with said cutting edge.

95 18. A machine for operating upon sheet material having, in combination, a tool carrier movable substantially parallel to the direction of feed of the material, a scalloping

tool mounted thereon and a work contacting feed element mounted upon said carrier and arranged to resiliently engage the material substantially within the bounds of the incision made by the tool.

19. In combination, a perforating machine having a reciprocable punch carrier, a punch holder arranged for operative engagement with said carrier, means for securing said holder in operative position relatively to said carrier and means independent of said securing means for temporarily retaining said holder in operative position.

20. In a perforating machine, in combination, a reciprocable punch carrier, a punch holder, clamping means for operatively securing said holder in position relatively to said carrier, and means constructed and arranged to prevent inadvertent separation of said carrier and holder upon release of the clamping means.

21. In a machine of the class described, in combination, a reciprocable punch carrier comprising a tubular member having a longitudinal slot in one of its walls, a punch holder provided with a part arranged for insertion within said tubular member, means for drawing the opposed edges of said slot toward one another to clamp said tubular member about said part, and interengaging elements carried by said member and part respectively for preventing their inadvertent separation.

22. In combination, in a machine of the class described, a tubular punch carrier of resilient material having a longitudinal slot in its wall, a clamping screw having engagement with said carrier at opposite edges of said slot whereby the internal diameter of said carrier may be decreased by drawing the edges of said slot toward one another, a punch holder having a cylindrical part arranged to be inserted within said carrier and to be clamped therein by the action of said screw, said part having a circumferential groove, and an element projecting from the interior wall of said carrier and arranged to snap into said groove upon insertion of said part within the carrier.

23. A perforating machine having, in combination, a tubular punch carrier of resilient material having a longitudinal slot in its wall, means for drawing the opposite edges of said slot together to decrease the interior diameter of said carrier, a punch holder having a cylindrical part arranged to be inserted within said carrier and to be clamped therein, said part having an external, circumferential groove, and an arcuate rib projecting from the interior wall of the carrier and arranged to snap into said groove upon insertion of said part within the carrier.

24. In combination in a perforating machine, a reciprocable punch carrier comprising

ing a tubular portion provided with an open extremity, said tubular portion being longitudinally slit at one side adjacent its extremity, arcuate ribs upon the interior of said tubular portion and extending in opposite directions from the slit therein, and a punch holder having a sleeve member arranged to project within the open extremity of said carrier and provided with a circumferential groove for engagement by said ribs.

25. In a perforating machine, in combination, a punch carrier comprising a tubular member having a longitudinal slot through its wall at one of its extremities, a punch holder provided with a part arranged for insertion within said tubular member, and to be clamped therein, said part having a circumferential groove, and a pair of arcuate ribs projecting from the interior of said tubular member upon opposite sides of said slot and of gradually decreasing radial height as they recede from said slot, said ribs arranged to snap into said groove upon insertion of the punch holder part within said tubular member.

26. A machine of the class described having, in combination, a reciprocable punch carrier, a punch carried thereby, and a work feeding element mounted upon said punch carrier and movable therewith, said element having a work contacting surface of considerable extent.

27. A machine for operating upon sheet material having, in combination, a reciprocable tool carrier, a tool mounted thereon, and a yieldable work contacting feed element associated with said carrier and reciprocable therewith, said element comprising a work contacting foot of substantially 100 crescent shape.

28. In a perforating machine, in combination, a reciprocable punch, a carrier therefor arranged to have imparted thereto a work feeding movement, a paper strip for supporting the material in opposition to the blow of the punch and movable intermittently in the direction of feed in time with the movement of the carrier, and a work feeding element mounted upon the carrier comprising a rod reciprocable toward and from said paper strip and a work engaging foot fixed upon the extremity of said rod.

29. A machine of the class described having, in combination, a punch carrier reciprocable in a direction parallel to the feed of the work, a punch carried thereby, and an element for feeding the work, said element being reciprocable in time with the punch carrier, and comprising a work engaging foot of substantially crescent shape arranged to partially encircle said punch.

30. A machine of the class described having, in combination, a punch carrier reciprocable in a direction parallel to the feed

of the work, a punch carried thereby, and an element for feeding the work, said element being reciprocable in time with the punch carrier and comprising a work-engaging 5 foot arranged substantially concentric with the punch.

31. In a perforating machine, in combination, a hollow punch having a tubular shank, and a holder for the punch comprising a 10 pair of separably connected members, one of said members having an opening therein of a diameter substantially equal to the external diameter of the punch shank, said opening and shank being so shaped as to prevent 15 the shank from passing completely through the opening, and the other of said members having an opening co-axial with the first opening and of a diameter substantially equal to the internal diameter of the punch 20 shank.

32. In a perforating machine, in combination, a hollow punch having a tubular shank, the rear end of said shank being of a diameter greater than the opposite end, and a

holder for said punch comprising a pair of 25 disk members one of said members having an opening therethrough of a shape and size to permit said punch shank to seat snugly therein, and the other of said members having an opening co-axial with said 30 first opening but of lesser diameter, and means for securing said members in superposed relation.

33. In a perforating machine, in combination, a hollow punch having a tapering 35 shank, and a holder for said punch comprising a pair of superposed disks and means for securing said disks in juxtaposition, one of said disks having a tapering opening 40 therethrough for the reception of said punch shank, and the other of said disks having an opening co-axial with said first opening but of a diameter substantially equal to the internal diameter of said shank.

In testimony whereof, I have signed my 45 name to this specification.

DONALD NOBLE.
